[57] CLAIM

The ornamental design for a medical control panel for an irrigation, lavage and suction apparatus or the like, as shown and described.

DESCRIPTION

FIG. 1 is a perspective view of a medical control panel for an irrigation, lavage and suction apparatus or the like showing my new design;

FIG. 2 is a front view thereof;

FIG. 3 is a side view thereof.

The rear of the control panel is plain and unornamented.

FIG. 3

FIG. 2

FIG. 1
